METAL CONTAINER

William E. Coakley, Milwaukee, Wis., assignor to
Pressed Steel Tank Company, Milwaukee, Wis.,
a corporation of Wisconsin

Application February 13, 1936, Serial No. 63,689

2 Claims. (Cl. 220—15)

This invention relates to an improvement in containers and more particularly to improvements in metal containers for beverages, as, for example, beer barrels, and the like.

The present invention is embodied in that type of container which includes inner and outer shells with insulation therebetween.

This application is, in respect of certain embodiments of the means which it contemplates for combining the bung and tap bushings with the inner and outer shells of the barrel, a continuation in part of my application for Metal containers, filed October 15, 1934, Serial No. 748,319.

One of the principal objects of the present invention is to provide means for so positively and mechanically interconnecting the shells that relative shifting therebetween and consequent building up of stress at localized points or areas with resultant fracturing and leakage will be avoided.

Another object of the invention is to accomplish this desirable interconnection between the shells in a simple and practical manner and in a way requiring a minimum amount of parts and consistent with economical production on a large scale.

Another object of the invention is to provide a receptacle of this character which is simple, compact and well balanced in construction, rugged and durable in use, and so constituted as to minimize exchange of heat between the contents of the container and the exterior.

Another object of the invention is to so construct and organize a receptacle of this character as to provide for permanent, effective and satisfactory interconnection of the bung and tap bushings therewith and this in such manner as to avoid any internal crevices or ridges which tend to preclude effective and expeditious cleansing of the interior of the receptacle.

Other objects and advantages reside in certain novel features of the construction, arrangement and combination of parts which will be herein-after more fully described and particularly pointed out in the appended claims, reference being had to the accompanying drawings, forming a part of this specification, and in which:

Figure 1 is a view partly in transverse vertical section and partly in elevation showing a metal container embodying the present invention;

Figure 2 is a fragmentary sectional view similar to Figure 1 but on an enlarged scale and illustrating one structure of the tap rod bushing and the parts of the barrel associated therewith;

Figure 3 is a similar view but illustrating the bung bushing and the parts of the barrel adjacent thereto as constructed in accordance with one embodiment of the invention;

Figure 4 is still another transverse sectional view on an enlarged scale showing the manner in which the inner and outer shells are positively interconnected in the region of the low point of the barrel;

Figure 5 is a fragmentary view in vertical section illustrating a specifically different means for connecting the tap bushing with the inner and outer shells;

Figure 6 is a fragmentary view of the structure shown in Figure 5 viewing the same from line 6—6 thereof;

Figure 7 is a fragmentary view in vertical cross section illustrating a specifically different way of organizing the bung bushing with the inner and outer shells;

Figure 8 is a fragmentary view in elevation viewing the bung bushing shown in Figure 7 from the exterior of the barrel with parts broken away and shown in section for the sake of illustration; and

Figure 9 is a fragmentary view similar to Figure 8 but showing different parts broken away.

Referring to the drawings, and more particularly to Figures 1 to 4, inclusive, it will be seen that the container or barrel in one embodiment of the present invention comprises generally an inner shell S and an outer shell or jacket J with insulation I interposed between the body portions of the shells and insulation H between the heads of the shells.

The inner shell S is made up of two tub-like sections designated at 1 and 2, the edges of the body portions of the open ends of which are brought into abutting relation and welded together as at 3. Preferably, the closed ends or heads 4 of the sections of the inner shell are dished or crowned as shown in the drawings.

The jacket or outer shell J is also made up of a pair of tub-like sections designated at 5 and 6 which surround the sections of the inner shell in the assembly although disposed in spaced relation thereto. The edges of the open ends of the body portions of the sections 5 and 6 of the outer shell are bent back or curled as indicated at 7 and these curls are brought into abutting relation and welded together as at 8. In this respect the container of the present invention embodies features described and claimed in my application for Metal barrel, filed November 6, 1933, Serial No. 696,755.

The closed ends of the sections of the outer shell or jacket J are cupped as indicated at 9 in order to provide the chime structure of the barrels.

- 5 The insulation I and H interposed between the shells may take any suitable form but preferably is of the structure and nature disclosed in my application for Metal containers, filed October 15, 1934, Serial No. 748,319.
- 10 A tap bushing designated generally at 12 is provided in the top of the barrel and is of conventional construction, although combined with the inner and outer shells of the barrel in a novel manner. In the structure shown in Figures 1 and 2, the tap bushing 12 is a forging and its peripheral portion at its lower or inner end is welded to the upper head 4 of the inner shell as indicated at W. Prior to welding the tap bushing to the inner shell a protective ring or annulus of metal 17 is slipped over the bushing and held up against the lugs 12' thereof by tack welding or in any other suitable manner. After the weld W has been formed the ring 17 is released from the lugs 12' and drops down to the position shown in 25 the drawings. Its purpose is to protect the weld W during the formation of the weld 18 which unites the margin of the tap opening in the outer head 10 to the tap bushing intermediate its ends. In forming the weld 18 sufficient metal is supplied to fill in the opening in the head of the outer shell or jacket J.

A bung bushing 16 which may also be a metal forging is provided between the inner and outer shells and is welded to the inner shell as indicated at 35 16^a and the outer shell as indicated at 16^b. The weld 16^a may be between the margin of an opening in the inner shell and a shouldered portion 16' of the bushing 16. Similarly, the weld W employed between the tap bushing and the inner shell may be between a portion of the inner shell which abuts a recessed or shouldered portion 13' of the tap bushing.

It will be seen from the foregoing that the tap bushing 12 and bung bushing 16 mechanically interconnect the inner and outer shells at two points and thereby tend to maintain the same in proper spaced relation. In this action these bushings are aided by the insulations H and I. In some instances, however, the inner shell shifts or tends to shift with respect to the outer shell and where shifting occurs stress is built up at the two points where the inner shell is secured to the outer shell, namely, in the region of the tap and bung bushings. This concentration of stress may result in fracturing either the welds or the inner shell at or near either one of these two points. Thereupon leakage of the contents will take place between the inner and outer shells and the container is rendered unfit for use.

60 The present invention proposes to preclude any such concentration of stress and consequent fracturing and leakage and accomplishes this by providing means which coacts with the bung and tap bushings to provide a three-point suspension of the inner shell on the outer shell.

In effecting this three-point suspension a steel circular plate 20 which is of approximately the same gauge material as the inner shell is welded as at 21 to the exterior of the lower end head 4 opposite the low point L of the inner shell. A hole 22 which may be approximately one-inch in diameter is punched or drilled in the outer shell in such position that it will come directly under the plate 20 when the shells are assembled. After the weld 8 has been formed the portion of the

outer shell which surrounds the opening 22 is then welded as at 23 to the plate 20. This welding may be just simply a bead between the margin of the opening 22 and the plate 20 or the hole 22 may be entirely filled up by supplying additional metal during the welding operation.

With this construction the inner shell is supported on the outer shell at three points and in such manner that relative shifting and concentration of stress is avoided.

10 In addition to the foregoing, the outer shell has integrally formed therewith outwardly directed corrugations 25 above and below the bung bushing 16. These corrugations extend entirely around the barrel and provide rolling hoops 15 which improve the handling of the barrel in that they make it possible to roll the barrel in a straight line without the use of skids. The hoops also serve to protect the exterior finish of the barrel by localizing the points of contact when 20 the barrel is rolled.

The manner in which the tap and bung bushings may be organized with the inner and outer shells to accomplish the purposes of the present invention and to realize certain other purposes 25 may be varied, although in all instances it is usually desirable to have these bushings not only serve their purposes in connection with the cleaning and filling and dispensing of the contents but also to mechanically function in maintaining the 30 inner and outer shells in proper position relative to each other. Thus, as illustrated in Figures 5 and 6, the tap bushing, there designated at 30 which is substantially similar to the tap bushing 12 and of conventional construction in its main 35 features, may be recessed or cut away as at 31 to permit of the flanging up of the portion 32 of the upper end head 4 of the inner shell S, as illustrated in Figure 5. The portion 32, which is the marginal portion of the opening provided in the 40 upper head 4 for the tap bushing, is then welded to the tap bushing as indicated at 33. The outer periphery of the inner end of the bushing is also welded to the upper end head 4 of the inner shell as indicated at 33'. As in the other embodiment 45 of the invention, a protective ring or annulus of metal designated at 17 is provided in order to protect the weld 33' during the formation of the weld 18 between the portion 10 of the upper end head of the outer shell or jacket J and the intermediate portion of the bushing 30.

A somewhat similar though specifically different means is provided for organizing the bung bushing shown in Figures 7 to 9 and designated at 40 with the inner and outer shells of the barrel. The bushing 40 is conventional in its construction except for the provision of a recess 41 to receive a flanged up portion 42 of the inner shell. Portion 42 is welded as at 42' to the bushing 40. The bushing 40 also has its outer periphery at its inner end welded to the inner shell as indicated at 43. The outer end portion of the bushing is received in an opening in the outer shell or jacket J, which opening is designated at 44 and indicated in dotted lines in Figure 9. The portion of the outer shell surrounding the outer end of the bushing is displaced inwardly slightly and then welded to the bushing as indicated at 45. After the welds are formed they are smoothed down in a suitable manner so as to leave a smooth 70 flush surface.

While I have shown and described several constructions in which the invention may be advantageously embodied, it is to be understood that these constructions have been selected merely for 75

the purpose of illustration or example, and that various changes in the size, shape and arrangement of the parts may be made without departing from the spirit of the invention or the scope of the subjoined claims.

5 The invention claimed is:

1. A container of the character described comprising inner and outer shells, the inner and outer shells being made up of tub-like sections welded together in the assembly, a tap bushing welded to the upper end heads of the inner and outer shells, a bung bushing welded to the body portions of the inner and outer shells, a plate welded to the lower end head of the inner shell in ver-

tical alinement with the tap bushing, the lower end head of the outer shell having an opening underlying said plate and a weld between the margin of the opening and said plate.

2. A metal container of the character described comprising inner and outer shells, means for securing the shells in spaced relation and an auxiliary support and connection between the shells comprising a plate welded to the inner shell, the outer shell having an opening overlying the 10 plate, and a weld between the margin of said opening and said plate.

WILLIAM E. COAKLEY.
